Case 3.

Eliphilet Wolf

Letters Patent

The schedule referred to in these Letters Patent and making part of the same, containing a description in the words of the said Eliphilet Wolf, himself of his improvement in the construction of the vertical plate & in the manner of combining the same with the back for inclosing the inlet for fuel in an anthracite coal stove.

Case No. 3.

Specification of an improvement made in the constructing the vertical plate & in the manner of combining the same with the back containing mica, or other lamina for illuminating the front of an anthracite coal stove having its inlet for fuel at top.

Whereas inconvenience has arisen from the falling out of ashes on opening the illuminating back in front when hung as usual at the side or top, also from the waving of a fixed front plate especially when of considerable horizontal extent. Therefore certain improvements, perfected & tested by repeated experiments are now intended to be introduced into general use; which improvement consists in making use (in place of one entire fixed plate) of a plate composed of two or more vertical sections of about four or five inches each, in horizontal extent; whencever the central opening in the front, to be occupied thereby is large enough to admit of more than one such section in which case said sections arranged edge to edge at small distances from each other in the same vertical plane, are to be combined in the central opening of the front with a back for illuminating the same in such manner that said plate, whether consisting of one or more sections, shall occupy the interior position being at top & open inward & that said back shall occupy the exterior position being at bottom & open outward, and that space shall be left between the two of about one inch, for

76374

for the ascent of air, & the descent of ashes which may be effected by placing interior brackets on the front plate at the upper margin of its central opening & exterior brackets at the lower margin of the same; the former for receiving corresponding projections cast on the upper margin of the gate and the latter base on the under margin of the back - for further information reference must be had to the drawings & explanations herewith appended.

Summary

The improvement above contemplated consists in preventing in anthracite coal stoves having their inlet for fuel at top, the falling out of ashes & the wavying of the front gate, by dividing the same vertically into sections of four or five inches each, no or less in horizontal extent, when the space to be occupied is sufficiently large to admit of such divisions & by combining the same whether so divided into sections or not, with its illuminating end in the central opening of the front, in such manner that said gate shall occupy the interior position, being at top, & swing inward; said back occupy the exterior position, being at the bottom, & open outward and that when shut a space of about an inch shall be left between the two for the ascent of air & the descent of ashes.

Therefore claim as my invention & improvement in anthracite coal stoves having their inlet for fuel at top, the preventing of the falling out of ashes, & the wavying of the front gate by dividing the same vertically into sections, as aforesaid, & whether so divided or not by combining the same with its illuminating end in front in the manner above set forth, together with the uses to which said improvement has been or may hereafter be applied irrespective of the inlet for fuel at top, & irrespective of every other provision with which the same may be combined in stoves or furnaces of any sort.
